UNITED STATES PATENT OFFICE.

JOHN F. CASEY, OF ST. LOUIS, MISSOURI.

TELEPHONE-EXCHANGE SYSTEM.

SPECIFICATION forming part of Letters Patent No. 394,833, dated December 18, 1888.

Application filed August 7, 1888. Serial No. 282,130. (No model.)

To all whom it may concern:

Be it known that I, JOHN F. CASEY, a citizen of the United States, residing at St. Louis, in the State of Missouri, have invented certain new and useful Improvements in Telephone-Exchange Systems, of which the following is such a full, clear, and exact description as will enable any one skilled in the art to which it appertains to make and use the same, reference being had to the accompanying drawings, forming part of this specification.

My invention relates more particularly to improvements in a telephone-exchange system known as the "Law system," which is shown and described in Letters Patent Nos. 220,874, 225,797, 278,613, 294,851, 319,856.

The object of the invention is to provide means whereby subscribers may call up the central office even though the call-circuit be broken and grounded between the subscribers and said central office. In the Law system a certain number of subscribers are located in a common call-circuit, but each subscriber is provided with an individual talking-circuit. In order for subscribers to obtain connections they first push in a button, which puts them in the call-circuit, and ask the central office for the subscriber desired. The central office signals the party desired over his talking-circuit, and then makes connection between the two subscribers. When subscribers have made their call, the button is allowed to resume its normal position and returns them to the talking-circuit in which their apparatus is normally located. It rarely happens that two subscribers call over the common call-circuit at the same time; but should this happen the call of one will be superimposed upon the call of the other, and the operator will receive both calls, or, if only one is received, the other subscriber must call again until his connection is made. In practice, however, no trouble from this cause arises.

All of the above is clearly set forth in the patents above referred to, and is alluded to herein to make the present specification complete in itself.

The call-circuit above referred to may be a complete metallic circuit, or it may be a circuit in which the ground is used as a return, in which case the subscribers, by pushing in their buttons before calling, connect them-

selves to ground and to the call-circuit, and thus complete said circuit, over which they may talk with the operator at the central station. I will herein describe my invention as applied to the latter kind of a call-circuit, and as also applied to the Law system; but I wish to have it understood that I do not limit myself to either of the same. Said call-circuits which I have described that use the ground for a return are known, generally, as "tree-wire calling-circuits," in that they consist of a main-trunk wire with branches therefrom running to the various subscribers. It often happens that said tree-wires become grounded between the subscribers and the central office, so that communication with the central office is cut off. In practice, however, the tree-wires run close to other wires, and even though the tree-wires be grounded between the subscribers and the central office the calls will reach said central office by the induction over the neighboring wires. It will be noted here that when a tree-wire is so grounded and the subscriber calls into it a complete circuit is formed from the subscriber to the ground by way of the tree-wire and returning by the ground to the subscriber's ground, so that the circuit is complete, and thus induction may take place between said tree-wire and the neighboring wires. Even though the tree-wire be not grounded the static capacity of the line will be such that when said tree-wire is used some induction will take place. With a ground the induction would of course be greater. It is found, however, that induction cannot be safely relied on to bring the calls to the central station. At least a safer mode of accomplishing the result is desirable, and this is the purpose of the present invention. When the call-circuit is broken or grounded, as I have described, it practically cuts a great number of subscribers from the central office, so that one break in said circuit is of more consequence than a break in the talking-circuits of several subscribers, for each one of said latter breaks cuts off but one subscriber. The importance of this subject has induced me to devise the present invention, which consists, briefly, in connecting the tree-wires with one of the talking-circuits, so that when a tree-wire becomes disrupted or grounded, as explained, the calls can be sent over the part

of the call-wire that is intact and one of the talking-circuits, which talking-circuit is used as a call-circuit for the time being until the tree-wire can be repaired, which often takes considerable time. The connection between a tree-wire and one of the talking-circuits is made in such a manner as not normally to have the tree-wire interfere with the operation of said talking-circuit as a talking-circuit. Nor does the talking-circuit when so connected with the tree-wire interfere materially with the functions of the tree-wire normally; but when the tree-wire is broken and the talking-circuit is used to transmit calls over, the talking-circuit cannot be used for talking purposes without breaking said connection and cutting off the calls, so that as a matter of fact, considering the talking-circuit alone, it may be said that it is at all times independent of the tree-wire. The aforesaid connection remains always intact between the tree-wire and the talking-circuit.

I will now describe my invention in detail by referring to the accompanying drawings, making a part hereof, in which—

Figure I is a diagrammatic view of the Law system provided with my improvements. Fig. II is a diagrammatic view showing the normal position of the circuits and devices of a subscriber's station provided with my improvements. Fig. III shows the same circuits and devices when the telephone is off the hook, which represents a case wherein the aforesaid subscriber is talking over his individual circuit to another subscriber. Fig. IV represents a case wherein the telephone is off the hook and the switch-button is pushed in, illustrating a case wherein the subscriber has taken his telephone off the hook and is asking the central office for a connection.

The same letters and figures of reference represent the same parts throughout the several views.

In practice I usually make the connection between the tree-wire and one of the talking-circuits at a subscriber's station, and preferably with the terminal subscriber. Figs. II, III, IV represent therefore the apparatus at a terminal subscriber's, all the apparatus at the other subscriber being the same, with the exception that the connection between the tree-wire and the talking-circuit and their contacts are omitted.

Having more particular reference to Fig. I, A B C represent sections of the Law switch-board, the section A being presided over by an operator, *a*, and the section B being presided over by an operator, *b*. *t* are the fixed terminals of the switch-board, and *t'* the flexible terminals of the switch-board. I have represented diagrammatically the fixed terminals by black dots and the flexible terminals diagrammatically by small circles, in order to readily distinguish the two from each other. In the patents above noted is clearly set out the operation, function, and construction of the fixed and flexible terminals.

1 represents a tree-wire, which is connected by branch wires with subscribers *S*, located at various points, and 2 designates the individual talking-circuits, which pass through the various sections of the switch-board to the various subscribers, where said wires are normally grounded. The branch circuits of the tree-wires are normally disconnected from the ground at the subscribers. Said subscribers by pushing in their button, as shown in Fig. IV, connect said branch wires with the ground, and complete the circuit of the tree-wire to ground by way of the bell-magnet, &c., and also to ground by way of the foregoing through the telephone transmitter and receiver, when the telephone is off the hook, as shown in Fig. IV, so that conversation may be carried on over said tree-wire with the switch-board operator at the central office. If now the tree-wire becomes grounded at any point, communication will be cut off between the subscribers between said ground and the central office. In order to enable me to receive such calls in spite of such a break of circuit, I connect the tree-wire 1 at any of the subscribers, but preferably the terminal one, with that subscriber's talking-circuit preferably by means of a condenser, 3, which arrangement is shown diagrammatically in Fig. I, the details thereof and the precise arrangement of circuits and devices being shown in the remaining figures of the drawings. In the diagram I have represented the individual talking-circuits by broken lines, so as to distinguish them from the tree-wires more readily.

Before describing the arrangement in detail I will state briefly how the invention is to be operated, so to more clearly set it forth. When a break occurs in the tree-wire, this fact, of course, becomes at once known to the operator presiding over said tree-wire at the central office. It is known, of course, which talking-circuit is provided with the condenser-connection, and I may say here in practice I select a talking-circuit for this purpose, which is comparatively idle, so that the invention may be carried out with greater success. The operator, knowing that her tree-wire is out of circuit, immediately inserts plug 4, which is connected with her receiver in the fixed terminal *t* of the talking-circuit which is to be used to receive the calls over. This is clearly shown in the lower half of Fig. I. The plug shown in the upper part of Fig. I is in its normal disconnected position. When the above connection is made, the calls may be received from the subscribers over the talking-circuit in the operator's receiver, which is suitably connected to ground. Thus all the calls between the break and the central office are received over the tree-wire, as before, so that every call sent in is received without interruption or diminution in volume and force at the central office.

In order now to explain how the condenser-connection does not interfere with the normal

operation of the lines and to set forth the construction and operation of the devices connected therewith recourse must be had to Figs. II, III, and IV.

5 1 is a branch of the tree-wire as it enters a subscriber's station, and 2 is an individual talking-circuit, as before.

10 6 is a switch which terminates in a button, 5, before referred to. This switch consists of 10 plates 7 and 8, mounted upon an insulating-base, 9. Adjacent to these plates are two plates 10 and 11, also mounted upon the base 9, the whole being moved by the button 5.

15 12 12 are two spiral springs, which are connected with extensions of the plates 7 and 8 and operate to draw the switch to its normal position when pushed in by the button 5.

20 13 14 are springs which normally rest upon the plate 10, and 15 and 16 are springs which 20 normally rest upon the plates 7 and 8, respectively. The tree-wire 1 is connected to the spring 14, and the spring 13 to the condenser 3. The spring 15 is in communication with the telephone-hook and the spring 16 with 25 the talking-circuit. Around the telephone-hook are arranged four contacts, 17, 18, 19, and 20, the two former being below said hook and the two latter being above the same. The contact 17 is connected to the other plates of 30 the condenser 3, and the contact 18 is connected with the transmitter T, and also in electrical communication with one of the spiral springs 12 and plate 8. The contacts 19 and 20 are in electrical communication with 35 the local circuit of the transmitter T, the said circuit being shown in dotted lines in order to distinguish the same more readily. When the telephone is taken from the hook, the hook rises and completes the circuit of the local 40 battery LB through the transmitter T. The terminal 19 is connected also through a bell-magnet, 21, to ground. A circuit, 22, connects the wire between the spring 15 and the telephone-hook with a spring that normally 45 rests upon the armature of the bell-magnet 21, which armature is also connected to the ground through the bell-magnet.

50 All of the foregoing shown in Figs. II, III, and IV, excepting the condenser, condenser-50 branch, and its contacts, make no part of my invention, the same being of the ordinary construction.

55 Fig. II shows the parts in their normal position, and illustrates how the calls are received at the subscribers and pass over the condenser branch to the talking-circuit 2 when the tree-wire is broken. The calls pass from the tree-wire 1 to the spring 14 over the plate 9 to the spring 13, charging the condenser 3, which charges the opposite plate thereof and causes a current to pass to the contact 17, to the telephone-hook, to ground by way of the circuit 22, armature, and bell-magnet, and also from said telephone-hook to 60 the contact 18, over spiral spring 12 to plate 8 and spring 16 to the talking-line 2, to plug 4, and operator's telephone and ground, as shown

in Fig. I. The current passing to ground by way of the bell-magnet and wire 22 will be wasted, but the current passing to contact 18 70 and line 2 will be sufficient to cause the call to be heard in the central office operator's receiver. When the subscriber having this condenser branch connected around his apparatus is signaled from the central office 75 and his apparatus is in its normal position, as shown in Fig. II, the current passes in a reverse direction to that set forth and indicated by the arrows in Fig. II as far as contact 18, from whence it passes through the 80 bell-magnet to ground in the same direction, indicated by the arrows. The greater portion of said current passes to ground through the bell-magnet by way of circuit 22 and bell-magnet armature and rings up the subscriber, 85 and the remaining portion passes to the condenser and line 1. This latter portion will not be sufficient to disturb the functions of the tree-wire, the condenser being of much 90 higher resistance than the bell-magnet. It will be noted also, as remarked above, that I select purposely an individual talking-circuit that is used but very little. Consequently such a wire would rarely be used for talking 95 purposes, and hence but few signals would be sent over said wire from the central office, and even when so sent they would not materially interfere with the function of the tree-wire. Such a talking-wire could be used as a call-100 circuit the greater part of the time without having its functions interfered with at all. To obviate this entirely, the operators at the central station would notify the subscriber that his circuit was not to be used as a talking-circuit until the tree-wire was repaired, 105 and the operators would not signal over the talking-circuits that are being so used. They would not call up such subscriber at all, but merely inform others desiring to talk with 110 such subscribers that they cannot do so for the present.

I will mention here that any number of subscribers may be provided with a connection between the tree-wire and their talking-circuits, so that should one subscriber's line be 115 out of order the calls may be still received over another subscriber's talking-circuit. As a matter of fact, it would not matter if each subscriber was provided with such a connection; but in practice one or two subscribers provided with the connection will be found to answer all requirements. Where more than one connection is made between a tree-wire and the talking-circuits and the subscriber 120 whose wire is being used temporarily to receive calls over is asked for by another subscriber, the operator can withdraw plug 4 from the former subscriber's circuit and connect said plug 4 with another subscriber's circuit, 125 which has the condenser-connection, and can then connect together the two former subscribers. In this way the subscribers whose circuits are used in cases of emergency as call-130

circuits are not inconvenienced in the slightest, it not even being necessary in this instance to sacrifice the one for the many, as mentioned below.

5 Fig. III shows the telephone off the hook, the subscriber being supposed to be talking over his circuit to another subscriber. In this instance the condenser branch is broken at the contact 17. Consequently the tree-wires 10 can never interfere with the individual wires when used for talking purposes. The talking-circuit, in this condition of affairs, should not be used to send calls over. In practice when the tree-wire is out of order and connection 15 is made with the talking-circuit by means of the plug 4, as described, the subscriber with whose talking-circuit connection is made will be notified by the central office that he cannot use his telephone until the 20 tree-wire is repaired, sacrificing the one subscriber for the time being for the good of the many. It will be noted that when the tree-wire is in order and the subscriber's wire is not being used as a call-circuit the subscriber 25 may use his talking-circuit the same as before. The arrows in Fig. III show the direction of the current, the current passing in this instance from the transmitter T to spiral spring 12, plate 8, spring 16, and line 30 2 to central office operator's receiver, to ground by way of same, to the bell-magnet 21, contact 19, telephone-hook through telephone-receiver and back to telephone-transmitter. The contact 18 and telephone-hook when in 35 communication with each other act to short-circuit the receiver and transmitter. This is the usual function of these parts and is no part of my invention. Should the central office signal the subscriber over his talking-circuit 2 while his telephone is off the 40 hook, the current will pass over the circuit indicated by the arrows in a reverse direction to that shown by said arrows and cause the bell to give one tap. This gives the operator 45 at the central office the busy test. This test is described in the patents aforesaid, and is also clearly set out in the application of Durant and Bailey, Serial No. 273,423, filed May 10, 1888. In this instance none of the signaling- 50 current passes over the condenser branch or tree-wire, as the circuit thereof is broken at the contact 17. In case the subscriber wishes to talk to the central office when the tree-wire is broken and his circuit is being used as a call- 55 circuit, he could do so, as clearly shown in Fig. III, without pushing in his button 5, but this would interfere with the calls, as pointed out above. In this case he would talk to the central office over his talking-circuit and not 60 over the tree-wire as ordinarily, for the central office operator's receiver is now in the circuit of his talking-wire, (see Fig. I,) so that the subscriber having the condenser-connection around his instrument is not as a 65 matter of fact cut off from the central office when his talking-circuit is being used as a call-wire.

In Fig. IV the button 5 is represented as having been pushed in, which brings the springs 13 and 14 on the plates 7 and 8, respectively, and the springs 15 and 16 both upon the plate 11, completing the circuit between them. This represents the condition of affairs when the tree-wire is in order and the subscriber is calling the central office 70 over said tree-wire for the purpose of getting a connection with another subscriber. If the tree-wire were broken, the subscriber could not, of course, communicate with the central office when his button was pushed in, as 80 shown in Fig. IV, but could do so by allowing his button to resume its normal position, as just pointed out above and shown in Fig. III. The arrows show the path of the current under the condition of circumstances shown in 85 Fig. IV. The current passes in this instance from the transmitter T over the spiral spring 12, the plate 8, the tree-wire 1, and ground, by way of same to the bell-magnet 21, by 90 way of telephone-hook and circuit 22 to transmitter and back to receiver. Should a signal be sent over the line 2 from the central office in this case, the current will pass from the spring 16 by way of the plate 11 to the spring 15, and from thence to ground by the telephone-hook and bell-magnet. The bell will 95 give one tap, as before, and the busy test will be given to the operator at the central office. None of the signaling-current can pass over the condenser branch, for as in the previous 100 instance the circuit thereof is broken at the contact 17. The circuit 22 merely acts to make and break the bell-magnet circuit when the telephone-hook is in the position shown in Fig. II—that is, it makes the bell-magnet 105 a vibrating one, the same acting as a rheotome.

I do not wish to limit myself to a condenser to make connection between a tree-wire and one of the talking-circuits, as any other kind of device having the same function could be used and still be within my invention. For instance, an induction-coil of high resistance could be used in lieu thereof, if desired. So, also, any means of switching and controlling the circuit at the subscriber's station could be used. Likewise, any other means of connecting the switch-board operator's receiver with the talking-circuit, instead of the plug 4 and connecting-wire, could be used and still be within my invention. I do not wish, therefore, to limit myself to the exact devices and arrangement set forth.

Having now fully set forth my invention and described its operation and usefulness, 125 what I desire to claim and secure by Letters Patent of the United States as my invention is—

1. The combination, with a telephone-exchange system having talking-circuits and 130 call-circuits independent thereof, of an electrical connection between any of said call-circuits and one or more of the talking-circuits, whereby when any of the call-circuits become

impaired the independent talking-circuits may be used as call-circuits.

2. The combination with a telephone-exchange system having talking-circuits and 5 call-circuits, of an electrical connection normally intact between said call-circuit and one or more of the talking-circuits, whereby when the call-circuit becomes impaired the talking-circuit may be used as a call-circuit.

10 3. A telephone-exchange system having a tree-wire call-circuit, as described, common to several subscribers, individual talking-circuits from said subscribers to the central office, and one or more electrical connections 15 between said tree-wire and said talking-circuits, for the purpose described.

4. The combination, with a telephone-exchange system, of a tree-wire calling-circuit passing to a number of subscribers and normally disconnected from the ground, as usual, 20 individual talking-circuits connecting said subscribers with the central office and normally grounded at said subscribers, one or more electrical connections between said tree-wire and one or more said individual talking-circuits, respectively, and means for connecting the switch-board operator's receiver with 25 said individual talking-circuit, for the purpose described.

30 5. The combination, with a call-circuit and a talking-circuit, of an electrical connection normally intact between the two, whereby when the calling-circuit becomes grounded the talking-circuit can be used to transmit the 35 calls sent over the calling-circuit, substantially as and for the purpose described.

6. The combination, with a telephone-exchange system of the type described, of a tree-wire calling-circuit of the character set 40 forth, common to a number of subscribers, individual talking-circuits passing from said subscribers to the central office and suitably grounded at said subscribers, a condenser branch between said tree-wire calling-circuit 45 and one of said talking-circuits, and a plug connected with the switch-board operator's

receiver, adapted to connect said receiver with said talking-circuit, substantially as and for the purpose described.

7. The combination, with a telephone-ex- 50 change system, of a tree-wire calling-circuit of the character described, common to a number of subscribers, individual talking-circuits grounded at the subscribers and passing to the central office, a subscriber's switch-button 55 adapted to connect said subscriber with the tree-wire calling-circuit or with the talking-circuit at will, a telephone-hook provided with the usual contacts, as set forth, an additional contact therefor, and a condenser and 60 condenser branch between the tree-wire calling-circuit and said contact, substantially as and for the purpose described.

8. The combination, with a telephone-ex- 65 change system of substantially the character described, of a tree-wire calling-circuit, as 1, individual talking-circuits emanating from a central office and grounded at the subscribers, one or more subscribers' sub-stations provided with a switch, consisting of plates 7, 8, 70 10, and 11, insulated from each other, and spring-terminal 14, connected with the tree-wire and normally bearing on the plate 10, the spring 13, also normally bearing on said plate 10, means for maintaining said switch 75 in its normal position, springs 15 and 16, bearing upon the plates 7 and 8 normally, and a push-button, as 5, operating said plates, a condenser branch and condenser connected with the spring 13, a telephone-hook having contacts 18, 19, and 20, as usual, an additional contact, 17, connected with the condenser branch, a bell-magnet, and electrical connections, substantially as and for the purpose 80 described.

In testimony whereof I have hereunto set my hand, this 4th day of August, 1888, in the presence of the two subscribing witnesses.
